United States Patent Office.

CALEB S. STEARNS, OF MARLBOROUGH, MASSACHUSETTS.

Letters Patent No. 100,082, dated February 22, 1870; antedated February 12, 1870.

IMPROVED LEATHER-SPLITTING MACHINE.

The Schedule referred to in these Letters Patent and making part of the same.

To all whom it may concern:

Be it known that I, CALEB S. STEARNS, of Marlborough, in the county of Middlesex, and State of Massachusetts, have invented an Improved Machine for Splitting Leather, of which the following is a full, clear, and exact description, reference being had to the accompanying drawings making part of this specification, in which—

Figure 1 is a perspective view of my improved machine.

Figure 2 is a transverse section through the center of the same.

Figure 3 is a perspective view of the brake with its roll.

In machines for splitting leather of the old construction a difficulty was experienced from the wrinkling or doubling up of the leather as it was pushed by the rolls against the knife, causing the leather to be cut of an unequal thickness, to remedy which objection a machine was constructed with a carrying cylinder provided with mechanism for grasping the end of the leather, as set forth in Letters Patent of the United States granted to me on the ninth (9th) day of February, A. D. 1864.

With the construction as described in the aforesaid Letters Patent that portion, however, of the leather held by the grasping mechanism was wasted.

To construct a machine in which this waste and also the wrinkling or doubling up of the leather is prevented is the object of my present invention, which consists in a yielding brake provided with a roller, in combination with a roughened carrying-cylinder, by which the leather is conducted to the splitting-knife, the under side of the brake being concave and corresponding to the curvature of the cylinder, whereby the leather to be split is held firmly down upon the latter up to the point where the knife-edge is placed, thus preventing the above mentioned wrinkling of the leather as it is pushed against the knife and entirely avoiding the waste incident to the grasping mechanism.

To enable others skilled in the art to understand and use my invention, I will proceed to describe the manner in which I have carried it out.

In the said drawings—

A is the frame-work of the machine.

B is the carrying-cylinder, the surface of which is milled or roughened so as to prevent the leather from slipping thereon, and thus insure its being carried forward as required.

The journals *a* of the cylinder B revolve in bearings *b*, which slide in slots *c* in the frame-work, and are pressed upward therein by means of spiral springs *d*.

C is the splitting-knife, which is secured by means of screws *e* to a longitudinal bar, D, the under side of

which is cut away, as seen in fig. 2, so as to afford a throat or passage, *h*, for the delivery of the "split" or waste.

E is a brake which extends longitudinally across the top of the carrying-cylinder B, and is provided at its outer ends with guide-blocks *g*, which slide vertically in slots *f* in the upper portion of the frame-work, the brake being pressed down toward the cylinder by means of spiral springs *i*, while the amount of its upward motion is regulated by the thumb-screws *G*, which thus serve to gauge the thickness to be given to the leather when split.

The under side of the brake is made concave, so as to fit the cylinder B, and smooth to allow the leather to slide freely under it until delivered by the revolution of the roughened cylinder B close up to the edge of the knife C, the concave surface of the brake projecting up to the edge of the knife to prevent the leather from wrinkling or doubling up on its passage thereto.

Near the outer portion of the brake E is formed a circular longitudinal recess, *k*, for the reception of and forming a bearing for a small roll, H, at one end of which is a gear, *l*, which is driven by a gear, I, at one end of the carrying-cylinder B.

The longitudinal recess *k* is open at its under side so as to allow the surface of the roll H to project slightly beyond the concave surface of the brake E and rest upon the leather, this roll, in connection with the cylinder B, serving to take hold of and carry the leather forward while it is being pressed against the cylinder by the brake.

The springs *i* are made lighter than the springs *d*, so as to allow the brake to be pressed up until arrested by the gauge-screws *G*, before the cylinder B can be depressed, and thus, when the leather is entered between the roll H and cylinder B and carried under the brake E, the latter is first raised until the guide-blocks *g* come into contact with the screws *G*, after which the cylinder B is depressed so as to allow the "split" or waste leather to pass under the knife C and out of the machine.

The "grain" is thus cut of uniform thickness throughout, and any unevenness caused by the varying thickness of the leather is thrown into the split. In case, however, a portion of the leather should be of a thickness less than that required for the "grain," the cylinder B will not be depressed, as the brake E will not be raised sufficiently to come into contact with the gauge-screws *G*, and consequently the thin portion of the leather will pass over the knife without being split, the spring-brake forcing the leather without regard to its thickness at all times firmly down upon the cylinder, and the leather is thus held securely in its proper position until delivered to the edge of the

knife, and entirely prevented from wrinkling or doubling up while being carried forward thereto.

The above-described machine has few parts, is of simple construction, and not liable to become disarranged, while it will perform its work in a thorough and superior manner.

Claim.

What I claim as my invention, and desire to secure by Letters Patent, is—

The yielding brake E with its concave under surface, in combination with the carrying-cylinder B and the knife C, the brake being so arranged as to hold the leather in position until delivered to the edge of

the knife, substantially in the manner and for the purpose set forth.

Also, the roll H, in combination with the yielding brake E and the carrying-cylinder B, substantially as and for the purpose described.

Also, the springs *i d*, in combination with the brake E and cylinder B, when the springs are so constructed and arranged that the brake will yield until arrested by the gauge-screws, before the cylinder can be depressed, substantially as and for the purpose set forth.

CALEB S. STEARNS.
